Primary Examiner — Keli L Hill(74) *Attorney, Agent, or Firm* — Plumsea Law Group, LLC**CLAIM**

The ornamental design for a loudspeaker, as shown and described.

DESCRIPTION

FIG. 1 is a perspective view of a loudspeaker showing our new design;

FIG. 2 is a front elevational view thereof;

FIG. 3 is a rear elevational view thereof;

FIG. 4 is a top plan view thereof; and,

FIG. 5 is a side elevational view of one side thereof, the opposite side elevational view being a mirror image thereof. The broken line showings form no part of the claimed design.
